UNITED STATES PATENT OFFICE.

MICHAEL LIPTAK, OF ST. PAUL, MINNESOTA, ASSIGNOR TO A. P. GREEN FIRE BRICK COMPANY, OF MEXICO, MISSOURI, A CORPORATION OF MISSOURI.

FURNACE WALL.

Application filed July 6, 1920. Serial No. 394,112.

To all whom it may concern:

Be it known that I, MICHAEL LIPTAK, a citizen of the United States, residing at St. Paul, in the county of Ramsey and State of Minnesota, have invented certain new and useful Improvements in Furnace Walls; and I do hereby declare the following to be a full, clear, and exact description of the invention, such as will enable others skilled in the art to which it appertains to make and use the same.

My present invention has for its object to provide certain important improvements in a construction of furnace walls; that is, of walls that must withstand intense heat. Such walls are used in connection with boiler settings.

It has been customary to build such walls partly of fire brick and partly of ordinary brick, with the fire brick on the inner or heat-exposed side; but in such older constructions, the fire bricks, which form the inner facing portion of the wall, have been tied or built into or interlapped with the ordinary bricks of the main portion of the wall in such manner that replacing of the fire bricks, when burned away, has been very difficult, requiring not only removal of the fire bricks, but tearing away of more or less of the main wall.

My invention provides an interlocking scheme or system, whereby the fire bricks, which constitute the inner facing wall, may be disconnected from and interlocked with certain of the bricks or blocks of the main wall without disturbing the latter. The various features of my invention, whereby the above noted and other advantages are obtained, are illustrated in the accompanying drawings, wherein like characters indicate like parts throughout the several views.

Referring to the drawings:

Fig. 1 is a perspective view showing a portion of a wall designed in accordance with my invention;

Fig. 2 is a perspective view showing a portion of the main wall and some of the interlocking elements of the inner facing wall;

Fig. 3 is a detail in perspective showing three of the lock tiles or blocks of a main wall;

Fig. 4 is a detail in perspective showing three of the lock blocks or bricks of the inner wall;

Fig. 5 is a perspective view showing a portion of the main wall with the inner wall removed therefrom;

Fig. 5^a is a view corresponding to Fig. 5, but illustrating a slightly modified arrangement;

Fig. 6 is a perspective view showing a portion of the main wall built up entirely of lock blocks or tiles;

Fig. 7 is a fragmentary plan view illustrating substantially the same construction that is shown in Figs. 1 to 5, inclusive, but modified to form a circular or cylindrical wall;

Fig. 8 is a perspective view illustrating substantially the construction illustrated in Figs. 1 to 5, inclusive, modified to form an outer facing wall as well as an inner facing wall, both of said facing walls being locked to the main intermediate wall;

Fig. 9 is a perspective view illustrating a further modification of the wall shown in Fig. 8;

Fig. 10 is a perspective view showing three lock blocks or tiles of the intermediate main wall illustrated in Fig. 9;

Fig. 11 is a plan view of a wall designed as shown in Figs. 1 to 5, inclusive, but with the bricks or blocks of the main facing wall laid together without an air space between the same;

Fig. 12 is a view corresponding to Fig. 11, but showing insulating material in the space between the main and inner facing wall;

Fig. 13 is a detail in perspective illustrating slightly modified forms of the lock blocks of the main and inner facing wall;

Fig. 14 is a perspective view showing three lock blocks of the inner facing wall properly assembled;

Fig. 15 is a view corresponding to Fig. 14, but showing the three blocks separated vertically;

Fig. 16 is a fragmentary plan view illustrating a modified form of the wall;

Fig. 17 is a detail in perspective showing two properly assembled lock bricks or tiles formed independently of and adapted to interlock with lock blocks or tiles of the main and inner facing wall; and

Fig. 18 is a perspective view showing a portion of a wall of still further modified construction.

The wall illustrated in Figs. 1 to 5, in-

clusive, will first be described, but before proceeding with the detail description thereof, the following statement should be made:

- 5 In accordance with my invention, the main wall may be a permanent structure, which may be re-lined with the fire bricks or inner facing wall as often as the latter may need replacing. From a broad point of view, this
 10 main wall may, in some instances, be made up of specially constructed lock blocks or tiles, but, as a very important feature within the generic scheme, I employ these lock blocks or tiles at intervals or different places,
 15 and for the main body of the main wall, I employ ordinary or commercial brick. Moreover, in the inner facing wall, I use, at certain intervals or different places, firebricks or tiles, the bodies of which are of the size
 20 of commercial fire brick, but are provided with projecting headed necks for interlocking engagement with the lock blocks or tiles of the main wall; and the main body portion of the inner facing wall is built up
 25 of standard or ordinary fire bricks.

In Figs. 1 to 5, inclusive, the commercial bricks of the main wall are indicated by the numeral 19, the lock blocks or tiles of said main wall by the numeral 20, the commercial
 30 fire bricks of the inner facing wall by the numeral 21, and the specially constructed lock blocks or bricks by the numeral 22. The bricks 19 of the main wall and the lock blocks or tiles 20 may be laid in cement or
 35 mortar or in any other suitable binding material. Of course, the commercial brick 19 may, when desired, also be fire brick, and the blocks 20 may be of fire brick tile.

The bricks 21 and 22 might, in some instances, be laid loosely together, but advisably are laid in fire clay or high temperature cement. The bricks and blocks above noted are laid in horizontal course and with lapped joints. The lock blocks or tiles 20
 45 are preferably of the same dimension transversely of the wall as the bricks 19, but, in a direction longitudinally of the wall, they are much wider. Also, the vertical dimensions or thickness of the bricks 19 and locks
 50 20 should be the same. The lock bricks or blocks 22 are the same thickness as the fire bricks 21, and are preferably of approximately the same width.

The lock blocks 20 are formed with vertical passages 20^a, that afford lock head seats to receive lock heads 22^a on the projecting outer ends of the lock blocks 22. The lock head seats 20^a are open at the inner edges of the blocks 20 through contracted head
 55 entrance throats 20^b that leave lock shoulders 20^c on each side of the seat 20^a.

The lock heads 22^a, of the lock blocks or bricks 22, are connected thereto by slightly contracted neck portions 22^b that form a
 60 lock shoulder 22^c at one side of said head,

The following important relation of parts should be noted:

The entrance throats 20^b are slightly wider than the heads 22^a, so that the latter may be inserted therethrough by endwise movements of the blocks 22; the lock shoulders 22^c, of the blocks 22, are engaged with one or the other of the lock shoulders 20^c by lateral movements of said blocks 22 after their heads 22^a have been inserted into the respective seats 20^a; the length of the necks 22^b is such that, when the blocks are interlocked, as best shown in Fig. 1, an air space 23 will be formed between the main and the inner facing wall; and when the two walls are built up, the lock blocks 22 will be held positively against lateral or horizontal movement, and hence, will be maintained in interlocking engagement with the co-operating lock blocks 20. Preferably, there is
 70 considerable clearance between the extreme outer ends of the heads 22^a of the blocks 22 and the outer walls of the seats 20^a, so that there will be no binding action between the interlocked blocks, due either to expansion
 75 or to replacements.

In the preferred arrangement, the lock seats 20^a are located considerably nearer one end than the other of the respective blocks 20, and the necks 22^b of the blocks 22 are
 80 formed by reducing the blocks at one edge only, leaving the other edge straight. This gives the proper arrangement when the alternate or vertically adjacent blocks 20 are offset to form lapped joints with the bricks 19 and successively reversed end for end, (see particularly Fig. 3, but note also Fig. 5, which shows that the blocks 20 thus set have their seats 20^a and necks 20^b in vertical alignment).

The lock blocks 22 of the inner facing wall are also offset to form lapped joints with the fire bricks 21, and are turned alternately with their lock shoulders 22^c on opposite sides, so that the vertically adjacent blocks 22 will have their lock shoulders 22^c engaged with shoulders 20^c that are on opposite sides of the vertical channel formed by the necks 20^b, (see particularly Figs. 2 and 4).

In Fig. 5^a, the lock blocks 20 are laid so that the vertical channels formed by the necks 20^b thereof, instead of running from top to the bottom of the wall, are set so as to form laterally offset vertical channels.

Fig. 6 illustrates a main wall made entirely of the lock blocks or tiles 20.

Fig. 7 illustrates exactly the same construction as illustrated in Figs. 1 to 5, inclusive, except that the bricks and blocks are slightly tapered and the wall is laid in circular form; and hence, in this view, corresponding parts are indicated by the same characters that are used in the description of Figs. 1 to 5, inclusive.

The wall illustrated in Fig. 8 involves all that is illustrated in Figs. 1 to 5, inclusive, in so far as it includes the main wall and the inner facing wall, but includes also a second facing wall, so that it is adapted for use as a division wall between two furnaces. Hence, the blocks of the two facing walls are indicated by the same characters. This arrangement, as will be noted, requires some of the lock blocks 20 to be set with their entrance throats 20^b facing inward and others to be set with their throats facing outward.

In the construction illustrated in Figs. 9 and 10, the two facing walls are formed of the same blocks or bricks as in the corresponding walls illustrated in Fig. 8, but the main or permanent wall, as shown, is composed of bricks 19^c and double facing lock blocks or tiles 20^c. These blocks 20^c are provided at both sides with the seats 20^a, entrance throats 20^b and lock shoulders 20^c.

The wall structure illustrated in Fig. 11 is like that illustrated in Figs. 1 to 5, inclusive, except that the necks 22^b, of the lock blocks 22, are so short that the blocks of the main and inner facing wall are brought closely together.

The wall structure illustrated in Fig. 12 is like that illustrated in Figs. 1 to 5, inclusive, except that the air space between the main and inner facing wall is filled with insulating material 24.

The construction illustrated in Figs. 13, 14 and 15 differs from the construction illustrated in Figs. 1 to 5, inclusive, only in that the anchoring blocks 20 are provided with lock head seats 20^a with entrance throats 20^b having lock shoulders 20^c on one side only, and further, in that one of each two adjacent lock blocks 22 has its offset portion 22^d on the opposite edge from its shoulder 22^c.

Figs. 16 and 17 show a wall structure in which both the outer or permanent wall and the inner facing wall are built up of the lock blocks 20 having the seats 20^a, entrance throat 20^b and shoulders 20^c formed therein, as already described. In this arrangement, the inner and outer blocks are locked together by independently formed lock blocks or bricks 25, each provided on one side and at both ends with shoulder-forming lugs 26 adapted to interlock with the shoulders 20^c of the blocks 20. The wide ends of these blocks 25 will pass freely through the throats 20^b and their lugs 26 are, as is obvious, adapted to be interlocked with the shoulders 20^c by lateral movement. Adjacent blocks 25 are laid with their lugs 26 projecting in opposite direction, so that they alternate their engagement with the lock blocks 20, (note particularly Fig. 17).

In the wall structure shown in Fig. 18, the permanent outer wall is the same as illustrated in Figs. 1 to 5, inclusive, and in Fig. 12, the insulating material 24 of Fig. 12

being also here shown. The lock blocks 22^c here employed are precisely like the blocks 22 in that they have the same head and neck structures, except that their body portions flare inwardly, so as to leave dove-tail spaces between adjacent columns of said blocks. These dove-tail spaces are filled in, as shown at 27, with a refractory filling material, such as broken fire bricks mixed with fire clay and high temperature cements applied while in plastic condition and then hardened.

As is well known, fire brick walls exposed to intense heat burn away and crumble down in short time and must be frequently replaced, while the outer main wall is seldom destroyed or damaged by heat, but, in the old system of making repairs, is usually very greatly damaged and frequently destroyed in making repairs. With my improved interlocking arrangement of blocks, the entire inner facing fire brick wall, or any portion thereof, may be readily replaced without in any way damaging the permanent wall.

While the inner facing wall built up of the fire bricks and blocks is somewhat superior to the filled in wall illustrated in Fig. 18, nevertheless, the latter is sufficiently good for many purposes and would use up broken fire bricks removed in making repairs and which would, otherwise, be waste. In all of the several forms, the permanent main wall and the inner facing wall are interlocked so that there is no possibility of splitting the two walls under the action of heat or other forces to which they are subjected in practice. Furthermore, new walls, as well as repairs, may be very quickly built up. The most practical form of wall is, undoubtedly, the one in which the maximum number of commercial bricks, either fire bricks or common bricks, are employed with just enough of the specially constructed interlocking blocks to provide the required bonding of the permanent and replaceable walls. Figs. 1 to 5, in particular, illustrate such construction. Where door spaces are to be formed, they would be made between adjacent columns of interlocking blocks, by the omission of commercial bricks at the proper place or places.

It is important to note that the interlocking of the head-equipped necks on the blocks of the displaceable inner wall with the lock seats in certain of the blocks in the outer or permanent wall is accomplished by movements of the head-equipped blocks in the space between immediately adjacent lower and upper layers of blocks or bricks. In the particular construction illustrated, the interlocking of the heads and seats is accomplished by a lateral horizontal movement of the head-equipped block and the heads are brought to positions of alignment with the seats by horizontal endwise move-

ments of said blocks, which carry the heads through the entrance throats that lead to the lock seats.

It is important to note that the blocks 22, when adjacent bricks 21 are removed, are adapted to be interlocked with or disconnected from the co-operating blocks 20 by movements in the direction of the plane of said blocks. Or, otherwise stated, by movements at right angles to or transversely of the entrance throats and head seats of the blocks 20 of the permanent outer wall. In Fig. 8, the wall heretofore, for convenience, designated as a permanent outer wall, becomes a permanent central wall; but is, nevertheless, an outer wall in respect to each replaceable facing or inner wall.

What I claim is:

1. A wall structure made up of a main masonry outer wall and a replaceable inner facing wall, one of said walls including blocks having lock head seats with entrance throats leading thereto, and the other wall including blocks having necks formed with lock heads, said heads being insertable into and removable from interlocking engagement with said seats by movement in the wall in the space between immediately adjacent lower and upper layers of blocks or bricks.

2. A wall structure made up of a main masonry wall and a replaceable facing wall, one of said walls including blocks having lock head seats with entrance throats leading thereto and the other wall including blocks having necks formed with heads, said heads being insertable into and removable from interlocking engagement with said seats by movement in the wall in a plane transversely of said entrance throat and seat, the said interlocking blocks being held interlocked when adjacent blocks of the replaceable wall are in position.

3. A wall structure made up of a permanent main wall and a replaceable inner facing wall, one of said walls comprising lock blocks with lock head seats and entrance throats leading thereto from one edge, and the other wall comprising blocks with necks formed with lock heads, the heads of said latter blocks being insertable into and removable from interlocking engagement with said seats, through said necks,

when adjacent blocks or bricks are removed, but being held interlocked when the adjacent blocks or bricks are in position, said seat-equipped blocks being built in columns and the space between the columns being filled in with commercial bricks, and said head-equipped blocks being built in columns and the space between said latter noted columns being filled in with commercial fire bricks.

4. A wall structure made up of a permanent main wall and a replaceable inner facing wall, one of said walls comprising lock blocks with lock head seats and entrance throats leading thereto from one edge, and the other wall comprising blocks with necks formed with lock heads, the heads of said latter blocks being insertable into and removable from interlocking engagement with said seats, through said necks, when adjacent blocks or bricks are removed, but being held interlocked when the adjacent blocks or bricks are in position, the seats of the first noted necks being nearer to one end than to the other, said seat-equipped blocks being built in columns with their ends alternately staggered and the space between the columns being filled in with commercial bricks, and said head-equipped blocks being built in columns and the space between said latter noted columns being filled in with commercial fire bricks.

5. A wall structure including a main or permanent masonry wall and a replaceable facing wall, said permanent wall being formed wall, said permanent wall being formed with lock-head seats with entrance throats leading thereto, and the other wall including blocks with lock-heads, said heads being insertable into said lock-head seats by endwise movements of the blocks having said heads and the said heads being movable into and removable from interlocking engagement with the said seats, by movements in a plane that extends transversely of the entrance throats of said seats, the interlocking blocks being held interlocked when adjacent elements of the wall are in position.

In testimony whereof I affix my signature.

MICHAEL LIPTAK.
